UNITED STATES PATENT OFFICE

BYRON M. SWEET, OF BARBERTON, OHIO

DESIGN FOR A STORAGE-BATTERY CASE

Application filed August 5, 1929. Serial No. 32,305. Term of patent 14 years.

To all whom it may concern:

Be it known that I, BYRON M. SWEET, a citizen of the United States, residing at Barberton, in the county of Summit and State of Ohio, have invented a new, original, and ornamental Design for a Storage-Battery Case, of which the following is a specification, reference being had to the accompanying drawings, forming a part thereof.

The figure is a perspective view of a storage battery case showing my new design. The design of the opposite side of the device is the same as that shown in the present figure.

I claim:

The ornamental design for a storage battery case as shown and described.
